UNITED STATES PATENT OFFICE.

FRED R. ALLEN, OF PROVIDENCE, RHODE ISLAND, ASSIGNOR TO UNITED STATES FLOOR SURFACING MACHINE COMPANY, OF PROVIDENCE, RHODE ISLAND, A CORPORATION OF RHODE ISLAND.

SURFACING-MACHINE.

939,373.

Specification of Letters Patent. Patented Nov. 9, 1909.

Application filed October 9, 1908. Serial No. 456,874.

To all whom it may concern:

Be it known that I, FRED R. ALLEN, a citizen of the United States, residing at the city of Providence, in the county of Providence and State of Rhode Island, have invented certain new and useful Improvements in Surfacing-Machines, of which the following is a specification, reference being had therein to the accompanying drawing.

- 10 This invention relates to floor surfacing machines, and has for its object to provide a portable machine constructed with a single upright spindle through which a plurality of power driven surfacing rolls may receive 15 a double motion which includes their being rotated on their own axes and also revolved about a common center.
- A further object of this invention is to provide means whereby the rolls may be rotated on their own axes but prevented from 20 rotating about the common center when in operation.

It is found in practice that a machine having surfacing rolls which move straight 25 ahead, or whose axes are fixed at right angles to the direction of travel, are best adapted for roughing out, that is, taking off the high places, such as the joints, butts, etc., of the floor. Such rolls are also adapted 30 to more readily follow the depressions and unevennesses in the floor and clean the same, while a machine having rolls which also revolve about a common center is the best for such purposes as finishing floors of 35 bowling alleys and the like, where a perfectly plane or level surface is required. The first mentioned arrangement of rolls, which removes but a small portion of the surface and cleans the same, making the 40 whole look bright and new, is desired in the majority of cases, as such a finish, on account of the saving in time, is much less expensive.

In carrying out my invention I provide a 45 machine which is adapted to be operated in either of the manners above described, and may be changed from the double motion machine to the single motion machine by simply disconnecting the two sets of mechanism and removing one set of the surfacing 50 rolls.

A further advantage of my improved machine is that all of the rolls may be removed

from their respective spindles and polishing or finishing blocks may be attached in place 55 thereof. By this construction it will be seen that with one machine a variety of work may be accomplished whereby any floor may be finished in exactly the manner required, either with a perfect surface, which is obtained by the double motion head, or a surface 60 may be cleaned and made approximately level with the straight ahead rollers, and either may be finished and polished by the application of the blocks, all by the 65 operation of a single machine.

With these and other objects in view, the invention consists of certain novel features of construction, as will be more fully described and particularly pointed out in the 70 appended claims.

In the accompanying drawings: Figure 1— is a side elevation of my improved machine partly in section. Fig. 2— is a plan view of the machine. Fig. 3— is a front 75 elevation of the roll head in section. Fig. 4— is a section on line 4—4 of Fig. 1. Fig. 5— is an enlarged view illustrating the carriage driving and reversing mechanism. Fig. 6— is an enlarged rear view showing 80 the locking pin for holding the steering handle in its up position. Fig. 7— is a detail illustrating the flexible head adjustment whereby said head is adapted to turn and allow the rolls to adjust themselves to any 85 unevennesses in the floor. Fig. 8— is a detail perspective view of the rear carriage wheel and the pivoted frame in which the same is mounted. Fig. 9— is a perspective view of a rectangular block adapted to be 90 carried by the head and take the place of the surfacing rolls.

Referring to the drawings, 1 designates the frame or body portion of the machine on which the motor 2 is mounted. The forward end of this body portion is provided with an upturned vertical plate 3 ribbed at 4—4 on either edge, in which plate the head supporting trunnion plate 5 is pivotally mounted. This body portion or carriage is 95 preferably mounted on three wheels the two forward or driving wheels 6—6, which are mounted in brackets 7—7 on shaft 8, are not allowed to pivot or swing, while the rear wheel 9 is mounted on shaft 10 in the yoke 100 11, see Fig. 8, to pivot or swing on the trun-

nion pin 12^a. In order to turn this wheel and guide the carriage while the same is being moved over the surface to be dressed a steering handle 12 is pivotally mounted at 13 in the outwardly extending ear 14 on said yoke, said handle being adapted to be turned upward to enter the socket or fork portion 15 on the frame where it is locked by means of the spring pin 16 to securely hold the steering wheel in its central or straight running position. The said front upturned or vertical plate 3 is provided with a central circular aperture 17, see Figs. 1 and 4, in which aperture the trunnion plate 5 is held by the retaining plate 18 and bolts 19, to rotate on the inwardly projecting or bearing portion 20. This trunnion plate is provided with two sets of ears 21—21 and 22—22 which are connected together through said plate and are also supported by means of the ribs 23—23 which extend between said upper and lower sets. Two pairs of independent supporting arms 24 and 25 are each pivoted at one end on the shafts 26 and 27, respectively, in said ears 21 and 22, the opposite ends of said arms being pivotally connected to the roll carrying head A at 28—28 and 29—29 respectively. This head is provided with an upper bearing 30 and a lower bearing 31 which bearings are joined together and supported in position by means of the circular conical shaped wall 32, the same being provided with an opening on its front side, for the purpose of admitting the worm and gear, hereinafter described, and is adapted to be closed by means of the plate 33 and secured in position by screws, not shown, thus forming a grease tight box in which said worm and gear are adapted to work. The lower bearing 31 is provided with a bushing 34, the lower end of which bushing is enlarged at 35 and is adapted to receive one end of each of the horizontal shafts 36 and rigidly support the same, said shafts being preferably four in number. Rolls 37—37 covered with surfacing material are mounted on said shafts and are adapted to be rotated on their own axes by the pinions 38—38 which are attached to said rolls and mesh with the beveled gear 39. This gear is fixed to the lower end of the upright shaft 40 which extends up through said bushing and through the upper bearing 30 and has the large gear 41 fixed to its upper end. This main upright shaft 40 is rotated direct from the motor 2 through the flexibly jointed shaft 42 and pinion 43 which pinion is mounted on shaft 44 in the bearing 45 supported above the bearing 30 by means of the double yoke arms 46. In order to obtain the rotation of said rolls about their common center I have secured a worm gear 47 to the upper end of the bushing 34 in which the roll shafts are mounted, and drive this worm gear by means of the worm 48 mounted on

the shaft 49, through the pulley 50 mounted on shaft 44, belt 51 and pulley 52, which latter pulley is mounted on said worm shaft 49.

Another feature of this invention is that the rolls 37—37 may be removed from their respective spindles and square, rectangular or poly-faced blocks, such as that represented in Fig. 9, may be covered with polishing or finishing material, means for tightening and retaining which may be mounted in said block, if desired. This block is also provided with a center bore to receive the roll shaft onto which said block may be secured. In order to raise and lower this head I have provided a hand operated lever 53 which is pivoted to the frame at 54, the lower end of said lever being pivotally connected at 55 to the sliding block 56 on one end of the connecting rod 57. The opposite end of this rod is connected to the lower end of arm 58, the upper end of said arm being fixed to the shaft 27, see Figs. 1 and 2. Springs 59 and 60 are arranged to engage either side of said sliding block 56, whereby a yielding pressure may be applied to the rolls while in operation, and when it is desired to adjust and regulate this pressure or raise the rolls entirely from the floor the handle 61 is raised to withdraw the spring actuated latch bolt 62 from the notched plate 63, allowing said lever to be moved and retained in any position to obtain the result desired. The tension of these springs may be regulated by means of the threaded nut 64.

The carriage is moved in a forward direction through the gear 65 which is mounted on the forward wheel shaft 8, see Fig. 5, gears 66 and 67, worm gear 68 and worm 69, which is mounted on the shaft 70, which shaft receives its rotary motion from the motor 2 through the pulley 71 belt 72 and pulley 73, see Fig. 1. When it is desired to reverse the rotation of the driving wheels 6—6 and move the carriage in the opposite direction a third, or idler gear 74 is provided which meshes with the gear 66 and is held in mesh with said gear by means of the bearing plate 75, which plate is pivotally mounted on shaft 76 and may be caused to swing gear 74 into mesh with gear 65 at the same time carrying pinion 66 out of mesh with said gear, when by driving from pinion 67 through pinion 66 and 74 gear 65 will rotate in the opposite direction and move the carriage backward. In order to operate and throw these gears to control the direction of the travel of the machine, an operating handle 77 is pivoted at its lower end on the pin 54 and is connected to the upper end of the gear bearing plate 75 by the arm 78 and connecting rod 79, whereby the raising of the spring actuated latch bolt 80, by the hand lever 81, will enable said lever to be moved and throw the gears either out of

mesh altogether with gear 65 to stop the carriage, or into position to drive the carriage either forward or backward. When it is desired a hood, not shown, may be placed around the surfacing rolls and connected by a pipe, not shown, to a blower 82 whereby the dust and waste material raised from the floor may be drawn from said hood forced up through the pipe 83 and into the receiving bag 84.

The operation of this device may be more fully described as follows: When the machine is not in operation the head controlling handle 53 is moved into the upright position, which raises the rolls clear of the floor. The carriage guide handle may then be withdrawn from its socket 15 and spring lock bolt to draw and guide the carriage into the position desired to commence the operation. Then as it is usually desired for the carriage to move ahead or backward in a straight line, the guide handle is turned upward into its inoperative position and holds the steering roll central. The motor is then started and the carriage operating handle 77 is carried into a position to connect the gears and cause the carriage to be moved into the desired direction. The rolls are then moved by means of the operating handle 53 to engage the surface to be dressed and the machine moves automatically along the floor, operating upon the same as it goes. When the end of the room is reached it is only necessary to move the reverse handle 77 from its forward to its back position when the carriage immediately reverses its motion and moves in the opposite direction.

An important feature of the invention is that the whole character of the machine may be changed and the surfacing rolls instead of receiving a double motion, which is that of rotating on their own axes and also around a common center, may be fixed by simply removing the worm driving belt 51 which will lock the bushing 34 and fix the rolls so that they will not rotate around a common center but only rotate on their own axes. In this way two of the rolls are set at right angles to the direction of travel while the other two rolls are removed from their respective shafts. By thus altering the machine the character of the work produced is entirely changed, rendering the machine adapted to clean the floor and produce a bright and finished surface much quicker than could be accomplished by the double motion head. Then again, when the head is used in this way the bolts 85-85 may be loosened and allowed to act against the springs 86, 86 permitting said head to rotate on its trunnion plate and adjust itself and allow the rolls to accommodate themselves to any unevenness in the surfaces over which they may pass while dressing the same.

65 This machine renders itself doubly val-

able by being adapted to be altered so as to accommodate itself to the different classes of work desired.

Having thus described my invention, what I claim as new and desire to secure by Letters Patent, is:

1. A surfacing machine comprising a portable supporting frame, a plurality of dressing devices carried by said frame, and adapted to be rotated either on their own axes or 75 about a common center, and means for holding said devices against one of said motions while performing the other.

2. A surfacing machine comprising a portable supporting frame, a plurality of dressing rolls carried by said frame, and adapted to be rotated on their own axes and also rotated about a common center, and means for locking said rolls against one of said motions while performing the other.

3. A surfacing machine comprising a portable supporting frame, a plurality of dressing rolls carried by said frame, a plurality of shafts on which said rolls are mounted, means for rotating said rolls on said shafts, 90 a sleeve for carrying said shafts, said sleeve being adapted to be rotated when desired and means whereby said sleeve may be locked against rotation while said rolls are being rotated.

4. A surfacing machine comprising a portable supporting frame, a plurality of dressing rolls carried by said frame, a plurality of shafts on which said rolls are mounted, means for rotating said rolls on said shafts, 100 a sleeve for carrying said shafts, and a worm and gear for rotating said sleeve.

5. A surfacing machine comprising a portable supporting frame, an upright roll carrying head, a plurality of rolls in said head, 105 an upper bearing and a lower bearing in said head provided with an inclosed space between them for containing lubricant, a sleeve for carrying a plurality of shafts on which said rolls are mounted, means for rotating said rolls, and independent means whereby said sleeve may be rotated or locked as desired while said rolls continue to rotate on their own axes.

6. A surfacing machine comprising a portable supporting frame, an upright roll carrying head, a plurality of rolls in said head, an upper main bearing and a lower main bearing in said head provided with an inclosed space between them, a sleeve for carrying a plurality of shafts on which said rolls are mounted, means for rotating said rolls, a worm and gear mounted in said inclosed space for either rotating or locking said sleeve as desired while the rolls continue 120 to rotate on their own axes.

7. A surfacing machine comprising a carriage, an upright roll carrying head supported from said carriage, a roll driving shaft in said head, a sleeve in said head for carrying 130

the shafts on which said rolls are mounted, and means for driving said sleeve and said shaft in the same direction at different relative speeds whereby said rolls are caused to 5 rotate on their own axes and also about a common center.

8. A surfacing machine comprising a carriage, an upright roll carrying head supported from said carriage, a roll driving 10 shaft in said head, a sleeve in said head for carrying the shafts on which said rolls are mounted, and a worm and gear for driving said sleeve, and gears for driving said shaft both in the same direction, but at different 15 relative speeds whereby said rolls are caused to rotate on their own axes and also about a common center.

9. A surfacing machine comprising a carriage, an upright roll carrying head supported from said carriage, a roll driving 20 shaft in said head, a sleeve in said head for carrying the shafts on which said rolls are mounted, said sleeve and said shaft being adapted to be driven in the same direction 25 at different relative speeds whereby said rolls are caused to rotate on their own axes and also about a common center, and means whereby said rolls may be prevented from revolving about a common center while 30 being rotated on their own axes.

10. A surfacing machine comprising a carriage, an upright roll carrying head supported from said carriage, a roll driving shaft in said head, a sleeve in said head 35 for carrying the shafts on which said rolls are mounted, a worm and gear for driving said sleeve and gears for driving said shaft both in the same direction, but at different 40 relative speeds whereby said rolls are caused to rotate on their own axes and also about a common center, and removable means whereby the rotation of said worm may be discontinued thereby locking said sleeve against rotation while said rolls continue to 45 rotate on their own axes.

11. A surfacing machine comprising a portable supporting frame, an upright roll carrying head, means for pivotally supporting said head from said carriage whereby 50 when the same is raised or lowered it is caused to maintain an upright position, a plurality of dressing rolls in said head, means whereby said rolls may be rotated on their own axes said rolls being also adapted 55 to be rotated about a common center, and means for locking said rolls against one of said motions while performing the other.

12. A surfacing machine comprising a carriage, a motor mounted thereon for driv-

ing the same, a manually operated means for 60 reversing the direction of said carriage, an upright roll carrying head, means for pivotally supporting said head from said carriage whereby when the same is raised or lowered it is caused to maintain an upright position, 65 a plurality of dressing rolls in said head, means for exerting a yielding working pressure on said rolls, means whereby said rolls may be rotated on their own axes said rolls being also adapted to be rotated about a 70 common center, and means for locking said rolls against one of said motions while performing the other.

13. A surfacing machine comprising a carriage, a plurality of dressing rolls carried by said carriage, each adapted to be rotated 75 on its own center and also about a common center, a motor mounted on said carriage for driving the same, a manually operated lever for reversing the direction of said carriage, a pivoted steering wheel, a handle located at the rear of the carriage for guiding said wheel and carriage, the carriage frame being provided with a recessed portion into which said handle is adapted to fit 80 to prevent said wheel from turning on its pivot, and means for locking said handle in said recessed portion.

14. A surfacing machine comprising a carriage, an upright roll carrying head supported from said carriage, and pivoting means whereby said head may oscillate laterally and allow the rolls to automatically 85 adjust themselves to the surface over which they are traveling.

15. A surfacing machine comprising a carriage, an upright roll carrying head pivotally supported from said carriage whereby the same may oscillate laterally and allow the rolls to adapt themselves to 95 the surface over which they are traveling, and yieldable means for controlling the extent of the lateral movement of said head.

16. A surfacing machine comprising a carriage, an upright roll carrying head 105 pivotally supported from said carriage whereby the same may oscillate laterally and allow the rolls to adjust themselves to the surface over which they are traveling and adjustable yielding means for controlling 110 the extent of movement of said head.

In testimony whereof I affix my signature in presence of two witnesses.
